CLAIM

The ornamental design for a sound level meter as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a sound level meter with the indicator light on.

FIG. 2 is a bottom perspective view of FIG. 1.

FIG. 3 is a top plan view of FIG. 1.

FIG. 4 is a bottom plan view of FIG. 1.

FIG. 5 is a left side elevation view of FIG. 1.

FIG. 6 is a right side elevation view of FIG. 1.

FIG. 7 is a front side elevation view of FIG. 1.

FIG. 8 is a back side elevation view of FIG. 1.

FIG. 9 is a front perspective view of a sound level meter with the indicator light off, it being understood that all other surfaces are the same as the other views of this embodiment.

The features shown in broken lines in the drawing depict surface indica and/or surface features and are not unclaimed borders, all broken lines depict unclaimed subject matter only and form no part of the claimed design
